Primary Examiner—A. Hugo Word*Assistant Examiner*—Cathy Anne MacCormac*Attorney, Agent, or Firm*—Wenderoth, Lind & Ponack[57] **CLAIM**

The ornamental design for a printer, as shown and described.

DESCRIPTION

FIG. 1 is a front and right perspective view of a printer showing my new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a right side elevational view thereof;

FIG. 7 is a left side elevational view thereof;

FIG. 8 is a sectional view taken on line VIII—VIII of FIG. 2 with the interior construction omitted;

FIG. 9 is another perspective view thereof;

FIG. 10 is a front top and right side perspective view of a second embodiment of FIG. 1;

FIG. 11 is a front elevational view thereof;

FIG. 12 is a top plan view thereof;

FIG. 13 is a rear elevational view thereof;

FIG. 14 is a bottom plan view thereof;

FIG. 15 is a left side elevational view thereof;

FIG. 16 is a right side elevational view thereof;

FIG. 17 is a sectional view taken on line XVII—XVII of FIG. 11 with the interior construction omitted; and,

FIG. 18 is another perspective view thereof.

The broken lines in FIGS. 9 and 18 are for illustrative purposes only and form no part of the claimed design.
